UNITED STATES PATENT OFFICE.

ULYSSES G. DETWILER, OF VERONA, PENNSYLVANIA.

RIVETING-TOOL.

1,100,230.

Specification of Letters Patent. Patented June 16, 1914.

Application filed February 17, 1913. Serial No. 748,959.

To all whom it may concern:

Be it known that I, ULYSSES G. DETWILER, a citizen of the United States, residing at Verona, in the county of Allegheny and State of Pennsylvania, have invented certain new and useful Improvements in Riveting-Tools, of which the following is a specification.

My invention consists of an improvement 10 in riveting tools and has for its object to provide a backing or resisting tool for the rivet being headed, so constructed as to absorb the shock of impact of the blows, while enabling the resisting tool to be continuously 15 maintained against the head of the rivet.

The tool comprises a holding handle or stem portion, a relatively movable anvil portion, an intervening cushion device, and a retaining key, constructed and adapted to 20 operate in the manner more fully herein-after described.

In the drawings illustrating one preferred form of the invention—Figure 1 is a view in side elevation, partly broken away, showing the tool in normal position for operation. Fig. 2 is a cross sectional view on the line II. II. of Fig. 1. Fig. 3 is a partial longitudinal sectional view showing a modified form of cushion. Fig. 4 is a sectional 25 view, similar to Fig. 2, showing the key in partly released position.

My improved tool is adapted to be held by the hand of the workman against the head of the rivet, to resist the blows by the 30 riveting or swaging tool at the other end, as will be readily understood. Ordinarily, especially where pneumatic riveters are used, such blows are rapid and continuous, resulting in a constant jar or series of shocks, together with resulting noise.

My invention is designed to reduce these objections to a minimum.

To this end it consists of a holding frame or main stem portion 2, preferably cylindrical in shape, the front portion of which is hollow, providing a cylindrical cavity within an extended shell 3. A handle 4 extends backwardly from the stem, of any suitable design or shape as desired.

The anvil 5 is provided with a recess 6 at its end and a rear cylindrical shank portion 7 extending inwardly of the cylindrical casing 3 and abutting against a resilient cushion 8 of rubber or other suitable material, an intervening metal washer 9 being preferably employed to receive the impact of the rear

end of anvil shank and protecting the cushion 8. These parts are preferably provided with central openings or holes 10, 11, respectively for facilitating the insertion of a removing tool of any suitable construction, as will be readily understood.

The body portion of the shank 7 between its inner end and the anvil head 5 is annularly recessed, as at 12, providing the reduced neck portion between terminal shoulders 13, 13.

The casing or shell 3 is apertured, as at 14 and 15, and adapted to receive the terminal 16 of the holding key 17 at one side 70 and the inwardly projecting extension 18 of the key at the other side, for the purpose of retaining the shank 7 within the casing.

Key 17 which may be of wire, is provided with a finger terminal 19, and is sufficiently 75 resilient to spring inwardly to the position shown in Fig. 2, and to be removed when it is desired to withdraw the shank for renewal of the cushion, or for changing to another anvil for a different size rivet head.

The recess 12 between the shoulders 13 is of sufficient length to provide for ample longitudinal movement of the anvil member within the cushioning capacity of the member 8.

In Fig. 3 the construction is the same as above described except that the cushioning element is made of a helical spring 8' of any desired strength.

The construction and operation of the invention will be readily understood and appreciated from the foregoing description. It may be of any desirable size, dimensions and proportions as to the size of the rivets being operated upon, or may be changed in other features or details by the skilled mechanic, but all such changes are to be considered as within the scope of the following claims.

What I claim is:

1. In a riveting tool, the combination with a handle portion consisting of a cylindrical shell having oppositely located openings therethrough and a rear holding grip, and provided with a resilient cushioning device 105 at the inner portion of the shell, of a one-piece freely rotatable anvil portion extending inwardly of the shell provided with an annular neck and limiting shoulders at each end thereof forming a key cavity, and a 110 resilient holding key embracing one side of the shell having an inwardly turned termi-

nal passing through one of the shell openings and into the key cavity and bent inwardly at the other end for the same purpose and then formed into a rounded finger terminal, substantially as set forth.

2. In a riveting tool, the combination of a cylindrical shell having a holding grip, an inner bearing portion, and oppositely located openings through the shell, a resilient cushion seating against the inner bearing portion, a freely rotatable anvil portion seating against the cushion and provided with an elongated annular recess or neck having terminal annular shoulders, and a half

round spring locking device turned inwardly 15 at one end for engagement of one of said openings and the annular shoulders and turned inwardly at the other end for the same purpose and then outwardly to form a rounded finger terminal, substantially as 20 set forth.

In testimony whereof I hereunto affix my signature in the presence of two witnesses.

ULYSSES G. DETWILER.
